UNITED STATES PATENT OFFICE.

DANIEL W. SHIEK, OF AURORA, ILLINOIS, ASSIGNOR TO LYON METALLIC MANUFACTURING COMPANY, OF AURORA, ILLINOIS, A CORPORATION OF ILLINOIS.

SHELVING.

1,376,835.

Specification of Letters Patent. Patented May 3, 1921.

Application filed November 11, 1918. Serial No. 262,000.

To all whom it may concern:

Be it known that I, DANIEL W. SHIEK, a citizen of the United States, residing at Aurora, in the county of Kane and State of Illinois, have invented a certain new and useful Improvement in Shelving, of which the following is a specification.

My invention relates to shelving, racks and the like, especially those constructed of metal, and the object of the invention is to provide a construction having transverse members which extend horizontally from one upright to the next, and serve as the support for the end members, which extend horizontally from front to rear and serve the dual purpose of binding the transverse members together and coöperating with them to carry the load.

I obtain my object by the mechanism illustrated in the accompanying drawings in which—

Figure 1 is a front elevation partly in section of shelving embodying my invention.

Fig. 2 is a plan section of the shelving, a portion of the shelf being broken away at the corners to exhibit the construction of the bars underneath.

Fig. 3 is a sectional elevation on the irregular line 3—3, Fig. 2.

Fig. 4 is a sectional elevation on the irregular line 4—4, Fig. 2.

Fig. 5 is a distributive view showing the relationship of the individual parts of the structure.

Fig. 6 is an assembly view of the parts shown in Fig. 5.

Similar numerals refer to similar parts throughout the several views.

In the form selected to illustrate the invention all the parts are of metal, the shelves 1 being formed of sheets and having depending flanges at the ends and at the front and rear edges. The form of shelf, however, is nonessential and the shelves may be omitted entirely if skeleton racks are preferred. In any event, the load is carried upon two transverse members 2, 2 and end members 4, 4. These are here shown in the form of angle bars, although their cross section may be altered without entirely departing from the spirit of the invention.

The bars are supported upon posts located at each corner of the shelf, the posts or uprights being here shown in the form of T

bars having a central limb 6 and transverse flanges 7, 7. The central limb of each bar has two vertical rows of apertures 8 and 9 arranged equidistantly both vertically and horizontally. In the preferred form here illustrated the apertures come in pairs, located at the same level. The apertures of the outer row 8 which are nearest the flanges 7 of the T bars are adapted to receive the hooks 10, 10 formed on the gusset 11 secured to the end bars 4. The plane of the gusset is vertical and parallel to the length of the end bar while the plane of the hook 10 is vertical but at right angles to the plane of the gusset. The parts are assembled by passing the heads of the hooks through the apertures and then lowering the gusset and bar whereupon the hooks will become seated and will securely engage the post. The end bars themselves are similar but the gussets which are fastened to them are different and may be considered as rights and lefts. The gusset 11, shown separately in Fig. 5, may be regarded as a left because its hook extends toward the left of the observer standing in front of the shelving. The gusset 15 shown near the left of Fig. 5 has two hooks 16, 16 which enter the inner apertures 9 of the post, and engage it upon the same principle as hooks 10. They may be regarded as rights.

The transverse bars 2 have gussets 22 at each end having hooks 21 adapted to seat in the socket 20 of gusset 11 and in a similar socket 25 in the gusset 15. The gussets 22 are all alike and the gussets 11 and 15 are all similar except that in the left gussets the sockets 20 are inside of the hooks 10 while in the right gussets 15 the sockets are formed outside of—that is, beyond—the hooks 16. This enables the hooks 10 and 16 to engage the same post without interfering with each other.

In assembling the parts the posts are first placed vertically after which the hooks 10 and 16 of the end bars 4 are passed through the apertures 8 and 9 respectively, in the central limb 6 of the post. The transverse bars 2 are then positioned, the hooks 21 being lowered into the sockets 20 and 25. This produces an interlocking effect and makes the structure rigid. Only three types of gussets are required, to wit, the left type 11, the right type 15 and the universal type 22. As the gussets on the end bars 4 engage

the post at two different points vertically, and as the gussets 22 engage the gussets 11 and 15 at different points vertically the parts are braced in every direction.

5 While it is not essential it is nevertheless advantageous to have the horizontal flanges of the bars 2 and 4, which extend inward toward the body of the rack, contact each other along mitered corners 27. This supplements the bracing action and produces a very rigid structure.

It will be noted that rivets, bolts, tie rods and similar fastening devices are totally dispensed with, thus rendering the assembling 15 a very simple matter and one which can be accomplished without the aid of any tools.

Having thus described my invention what I claim as new and desire to secure by Letters Patent, is:—

20 1. In a shelf support of the character described, a plurality of uprights, each provided with two rows of equidistant apertures, arranged longitudinally thereof, a plurality of transverse bars, each provided 25 at the ends thereof, with hook shaped extensions, adapted to engage any two apertures of a row that are in proximity to each other, and a plurality of bars provided with extensions at the ends, arranged to engage 30 said transverse bars.

2. Shelving having apertured posts, end bars hooking into said posts, and transverse bars hooking onto said end bars, the end

bars constituting rights and lefts whereby their hook portions may pass each other at 35 the same level.

3. Shelving having posts provided with two vertical rows of apertures, end bars, right and left gussets fastened to the respective end bars and hooking into the posts 40 at the same level, and transverse bars having gussets hooking onto the gussets of the end bars.

4. Shelving having posts provided with two vertical rows of apertures, end bars, 45 right and left gussets fastened to the respective end bars and hooking into the posts at the same level, each gusset hooking into the post at two vertically distant points, and transverse bars having gussets hooking onto 50 the gussets of the end bars.

5. Shelving having posts provided with two vertical rows of apertures, end bars, right and left gussets fastened to the respective end bars and hooking into the 55 posts at the same level, each gusset hooking into the post at two vertically distant points, and transverse bars having gussets hooking onto the 60 gussets of the end bars, the gussets of the transverse bars hooking onto the gussets of the end bars at two vertically distant points.

In witness whereof, I have hereunto subscribed my name.

DANIEL W. SHIEK.
